UNITED STATES PATENT OFFICE.

DANA E. HARDING, OF ARLINGTON, MASSACHUSETTS, ASSIGNOR, BY MESNE ASSIGNMENTS, TO HARDING-WOLCOTT COMPANY, OF BOSTON, MASSACHUSETTS, A CORPORATION OF MASSACHUSETTS.

GRADING AND GAUGING MACHINE.

Application filed October 22, 1923. Serial No. 669,909.

My present invention is a machine for gauging and grading sheet material of uneven or varying thicknesses, and is particularly adapted for operation upon entire 5 hides, skins or similar relatively large sheets of material. In addition to the gauging, grading or measuring devices, I provide indicating means to register the action of said devices, preferably in combination with automatically operated averaging mechanism, thus providing means for an indicator to be actuated through the independent operations of a plurality of gauging devices in contact with the work. My invention is particularly intended for use in connection with leather, and the tanning industry, wherein the hides, skins or the like require gauging and grading, and must be measured for thickness, weight or the like. Thus in sorting skins it is at present customary to grade the same into various weights from which can be subsequently cut or formed the different lines of articles such for example as uppers for use in the manufacture of boots 20 and shoes. Thus skins intended for this purpose are graded into "men's," "heavy men's," "light men's" and the like. As heretofore carried out this operation of grading hides and skins is a difficult one and 25 requiring great skill, the necessary operations up to the present consisting entirely in a hand operation. Thus each skin or hide was handled by one or more operators, the skin or hide being taken off the stack, pile or horse, the operator being obliged to manipulate the entire skin, bend the same in one or more places, and gauge or measure it by running the fingers along the bent portion. A highly skilled operator could thus 30 "guess" with fair accuracy the weight of the skin, by feeling the thickness, etc., as well as he could in this operation, thereby sorting the skins roughly into the various weights as above noted. In this laborious, 35 slow and inaccurate hand operation, it was of course impossible to have any predetermined uniformity in the resulting piles or stacks of skins and hides, thus roughly graded by guess work. One operator would 40 grade a hide as "light men's" or "light medium," whereas the adjoining operator would grade a skin of equal or even less thickness as one of the heavier classes. The 45 toughness of the grain was necessarily de- ceiving as to its thickness, and the bending 55 of the skin, which was a part of the operation, was of course deceiving and not a true index of its thickness, grade or weight. The difficulty in handling such large, uneven, and oddly shaped articles as hides and skins, 60 which also were of warped surface, necessarily resulting from the laying out flat of a hide which was removed from a rounded animal, has rendered it apparently impossible to handle such articles in this way by 65 a machine.

However, I have now devised a machine for this work, which will operate upon a hide or skin of any dimensions, and which will indicate the gauge, by measuring the 70 varying thickness of the same at any pre-determined point, width, line or section, and which machine will perform its operation with perfect accuracy, resulting in uniformity of product, and with great speed. 75 Furthermore, the operator is relieved from the laborious and tedious action of lifting, handling, bending and feeling each individual hide, skin or layer of leather, and of course my machine eliminates all guess work 80 and permits the heretofore highly difficult operation of gauging and grading hides and skins to be performed by unskilled labor with extreme accuracy and perfect uniformity. 85

In carrying out my present invention I provide mechanism which will receive, handle, measure at a plurality of points and feed through entire hides and skins, indicating the gauge, grade, weight, as the same 90 is fed through, these indications preferably being the resultant of a plurality of gauging, grading or feeling instrumentalities, which devices are operative instantly, continuously, as the skin is fed through, and 95 which are immediately set to operate upon a succeeding hide, as the preceding one is moved or fed through and out of the machine.

My improved construction visually indicates the average thickness of a hide or skin at a plurality of points along its length and the average thicknesses are indicated by a pointer moving over a graduated dial and the average thickness of a skin is determined by estimating the particular region of the indications with which the indicating hand is associated during the passage of a 100 105

skin through the machine. A fair operator will be able to determine this average thickness with considerable accuracy and an expert operator can do so with extreme accuracy.

My invention also contemplates the provision of means for forming visual indications as a permanent record of the to and fro travel of the indicating hand on the dial 10 and I therefore provide a record making sheet movable in synchronism with the movement of the hide or skin through the machine with which the marking device of the indicating hand cooperates. With relatively unskilled labor it may be preferable to depend on the permanent record for determining the grade of the hides gauged or as a check on ordinary or even skillful operators this feature of my invention is important.

In a device of this character where an indicating hand is controlled in its pivotal movement by a plurality of vertically movable devices, the variation or fluctuations of the indicating hand are apt to be so rapid as to cause difficulty in accurately and easily estimating the amount of movement and the relative position of the indicating hand on the dial. To obviate this difficulty and to provide an additional or second averaging device to be used in connection with the averaging device directly connected to the indicating hand, I have connected to the driving mechanism of the indicating hand a dash pot, either air or liquid, as may be desired, and which prevents sudden surges in the movement of the indicating hand, steadyng the same so as to have its variation in movement relatively slow and gradual, considered with respect to the longitudinal movement of the hide or skin through the machine. This feature I consider of great importance as it enables me to have in a single machine what is practically a double averaging device and which enables me to quickly and accurately estimate the average movement of the indicating hand without undue fatigue.

I believe that a machine of this type, capable of gauging, grading and measuring operations on such large and unwieldy articles of uneven shape and thickness as hides and skins, is a distinct novelty, and I wish to claim the various features and operations of my invention, broadly.

In the accompanying drawings illustrating the preferred embodiment of my invention,

Fig. 1 is a front elevation;

Fig. 2 is a sectional side elevation on the line 2-2 of Fig. 1;

Fig. 3 is a front elevation of a modification of the lifting means, and

Fig. 4 is a sectional side elevation on the line 4-4 of Fig. 3.

Referring to the drawings, 10 designates a base or table supported at any suitable height above the floor or ground by legs 11 and at the rear of said table and at each side thereof are vertically arranged angle members 12 secured to the table 10 by struts 13. Secured to the upper ends of the angle members 12 is a channel iron member 14. The top of the table or base 10 adjacent the angle members 13 is cut away, as indicated at 15, Fig. 2, and through which extends the surface of an elongated cylinder member 16 secured to a shaft 17 that is rotatably mounted in bearings 18 arranged on either side of the base 10 on the members 12. One end of the shaft 17 extends outward beyond the limits of the base or table 10, as clearly shown in Fig. 1, and has mounted thereon tight and loose pulleys 18 and 19 respectively. The upper surface of the table or base 10 is covered with a smooth surface material 20, such as zinc or the like, and it is to be noted that the width of the table 10 is wide enough to receive and have fed thereover from front to back a complete hide. In actual practice, therefore, the width of this base or table 10 is between five and six feet.

Secured to the front surface of the channel iron member 14 and arranged side by side is a plurality of yokes 21, these yokes 21 being secured to the channel shaped member 14 by bolts 22. Each of these yokes at its forward end is provided with an elongated slot 23 and in the slots 23 are mounted for vertical movement shafts 24. On the shafts 24 between the arms of the yokes 21 is rotatably mounted an idler pulley 25. The outer ends of the shafts 24 are rotatably mounted in the lower ends of yokes 26, the shafts 24 being held against endwise movement by cotter pins 27.

As shown in the present embodiment of my invention, there are four rollers or wheels 25 arranged in pairs, but it is obvious that I may utilize as many pairs of wheels 110 as I may desire or as may seem necessary. The wheels being arranged in pairs, there is secured to the top of each yoke 26 of each pair a bearing member 28 to which is pivotally attached the lower end of a link or 115 rod 29 and each of the links or rods 29 is pivotally connected at its upper end to the ends of a connecting link 30. Assuming that two pairs of wheels 25 are sufficient, it will be obvious that two connecting links 30 120 are employed and to the middle of each of the connecting links 30 is pivotally attached the lower end of a link or rod 31, the upper ends of these links 31 being pivotally attached to the ends of a link or rod 32. This link or rod 32 has pivotally attached to its middle point the lower end of a connecting rod 33, the upper end of this rod being pivotally attached by screw 34 to a circular member 35 that is rotatably mounted on a 130

shaft 36 secured to the front face of a member 37 that is secured to the upper face of the channel shaped member 14. A portion of the periphery of the circular member 35 is 5 provided with gear teeth 38 which mesh with, and drive, a pinion 39 pivotally mounted on the front face of the member 37 and extending radially outward from the pinion 39 is a hand or pointer 40 which cooperates with indications designated 41 on a dial plate 42 secured to the upper front face of the member 37 by screws 43. Limit stops 44 are provided on the front face of the dial plate 42 to limit the movement of the indicating hand 40. Formed integral with, and 10 extending laterally outward from, the circular member 35 is an arm 45 to the outer end of which is pivotally attached the upper end of a member 46 and the lower end of this member 46 is drilled and tapped to receive the upper threaded end of a piston rod 47. The lower end of the piston rod 47 has secured thereto a piston 48 which works in a cylinder 49 secured to the upper face of the 15 channel shaped member 14 in any suitable manner. Secured to the side of the member 37 by screws 50 is a bracket 51 which has formed thereon a shaft 52 that extends forwardly and has rotatably mounted thereon a brake lever 53, one portion 54 of which constitutes a brake shoe that is adapted to engage with the periphery of the circular member 35. The end of the brake lever 53 remote from the brake shoe portion 54 has 20 pivotally attached thereto the upper end of a member 55 which is mounted for sliding movement in arms 56 and 57 secured to the channel shaped member 14. The lower end of the member 55 adjacent the bearing 57 is bent at a right angle and extends forwardly and outwardly, as indicated at 58, and the strengthening bracket 59 is secured to the member 55 and right angled portion 58. The forward end of the portion 58 has 25 secured thereto by bolt 60 a downwardly depending yoke 61 in the lower end of which is rotatably mounted an idler wheel 62 and when the brake shoe portion 54 is in engagement with the periphery of the circular member 35 so as to prevent rotation thereof, the wheel 62 is in engagement with, or only slightly above, the top surface of the smooth surfaced covering 20 of the table or base 10. A spring 60 secured at one end to the member 37 by screws 81 bears on the projection 82 secured to the rear face of the member 55 and urges the member 55 and wheel 62 downwardly.

The base or table 10 and the covering 20 therefor are provided immediately beneath the idler wheel 62 with a rectangular slot through which extends an idler wheel 63, this idler wheel being rotatably mounted in a plate 65 secured by screws 66 to a member 67 that in turn is secured to the under sur-

face of the base 10. The base or table 10 on its under side is provided with a transversely arranged downwardly depending member 68 to the front face of which is secured a bearing plate 69 and in this bearing plate is pivotally mounted a link 70 at the lower or other end of which is rotatably mounted a pulley 71. Secured to the lower front face of the transversely arranged plate 68 is a member 72 through which extends a set screw 73 that is adapted to be brought into engagement with the link 70 intermediate the ends thereof and this set screw 73 is utilized to swing the link 70 about its pivot point on the lug 69 and thus bring the pulley 71 into engagement with the cylindrical pulley 16 and with the pulley 63. Power being transmitted to the cylindrical member 16 by the tight pulley 18, said cylindrical member rotates in the direction of the arrow shown in Fig. 2 and the pulley 71, engaging with the cylindrical member 16, is rotated and in turn rotates the pulley 63, which pulley, engaging with the pulley 62, rotates said pulley 62 in the direction of the arrow and feeding any material placed on the top of the table or base 10 to the right, as viewed in Fig. 2.

It is obvious that, if a sheet of material, such as leather, is placed on the top of the base or table 10 and fed to the right, as viewed in Fig. 2, between the cylindrical member 16 and the plurality of idler pulleys 25, said pulleys 25 will be lifted individually a distance above the upper surface of the table 10 equal to the thickness of the sheet of material at the particular point of contact. It is obvious that, if the thickness of the material is not a uniform thickness, the various idler pulleys 25 will be at different heights above the upper surface of the table or base 10 and this difference in height will be manifested through a varying upward travel of the members 29, 31, and 33 so that the difference in thickness of the material as measured by the various idler pulleys 25 will be indicated on the dial plate 42 by the extent of movement of the indicator hand 40. The operator, by watching the indicator hand 40, will be able to determine on which section of the dial 42 the major portion of the movements of the indicator hand 40 takes place and will thus be able to determine with considerable accuracy the average thickness of the hide being gauged. In order to provide a visual indication of the movement of the indicating hand 40, I may provide the dial plate 42 with parallel spaced perforations 83 and 84 respectively, and on the back of the dial plate 42 adjacent the slot 84 is arranged an arbor carrying a roll of paper 85, the end of this roll of paper passing through the slot 84, upward across the face of the dial plate 42 and rearwardly through the slot 83 where

its end is fastened to an arbor 86 mounted in suitable bearings (not shown) attached to the rear face of the dial plate 42. Secured to the end of the shaft 86 is a pulley 87 over which runs a belt 88, this belt also running over a pulley 89 secured to a shaft 90 that is rotatably mounted in bearing lugs 91 secured to the member 14. Also secured to the shaft 90 between the bearings lugs 91 is a pulley 92 which is normally out of engagement with the surface of the cylinder 16, but when the sheet of leather or other material, the thickness of which is to be gauged, is passed through the machine, it fills the space existing between the pulley 92 and the cylinder 16 and the pulley 92 is therefore rotated by means of the interposed material. Attached to the indicator hand or pointer 40 is a marking device 93 which engages with the sheet of paper 85. It is obvious, therefore, that, as the sheet of leather or other material, whose thickness is to be gauged, passes through the machine, a visual indication of the average thickness of such sheet of leather or other material at any particular instant will be made on the sheet of paper 85 so that it is possible to use the visual indication on the sheet of paper 85 in connection with the visual reading by the operator in connection with the indicating marks on the dial plate 42 and the accuracy with which the workman determines the average thickness of the leather may be checked up from time to time.

Referring now to Figs. 3 and 4, I have shown a modification of the mechanism shown in Figs. 1 and 2. Attached to the channel shaped member 14 are the bearing lugs or ears 94 provided with elongated bearing grooves 95 at their outer end and rotatably mounted in the bearing grooves 95 are shafts 96 which have secured thereto pulleys 97 similar in size and appearance to the pulleys 25. Secured to the upper edge of the front face of the member 14 by bolts 98 are brackets 99, one of such brackets being provided for each of the pulleys 97 and the pulleys 97 being assumed to be equal in number to the pulleys 25, as above described with respect to Figs. 1 and 2. Rotatably mounted on each of the lugs 99 by pin 100 is a bearing yoke 101 near the lower front end of which is rotatably mounted on pin 102 the idler pulley 103 which is normally in engagement with the periphery of the pulley 97 and is driven by such pulley. Secured to the front top end of each of the members 101 is a bearing plate 104 to which is pivotally mounted the lower end of a member 105. Pivotally mounted to the top of the member 105 is a member 106 which has pivotally secured to its top end a cross member 30 and, as the rest of this modification is similar in all respects to the mecha-

nism described with respect to Figs. 1 and 2, 65 it will not be further described.

The operation of this modification is identical with the form described with respect to Figs. 1 and 2 and a detailed description of the operation thereof is therefore not 70 considered necessary.

While I have shown and described the preferred embodiment of my invention somewhat in detail, it is to be understood that I may vary the size, shape, and arrangement of parts comprising my invention within wide limits without departing from the spirit of the invention. 75

My invention is further described and defined in the form of claims as follows: 80

1. A machine of the class described, having provision for feeding therethrough sheet material of uneven thickness and varying contour, in combination with a plurality of means responsive to the mean thickness of 85 said material, means actuated thereby to indicate said thickness in combination with means to maintain said indication after the passage of the material.

2. A machine of the class described, having provision for feeding therethrough sheet material of uneven thickness and varying contour, in combination with a plurality of means each responsive to variations in thickness, means actuated by the first named 95 means to automatically average such variations in combination with indicating mechanism operated by said second named means, and means for maintaining an indication of thickness during an intermittent period of 100 time.

3. A machine of the class described, having provision for feeding therethrough sheet material of uneven thickness and varying contour, in combination with a plurality of 105 means operative to find said variations in thickness, means operable thereby to automatically average such variations, in combination with means actuated by the second means for indicating the average thickness 110 so found and to preserve temporarily such indications after the material has passed.

4. In a machine of the class described, the combination of an averaging device for determining the average thickness of sheet material fed through said machine, said averaging device including a cylindrical pulley or drum, a brake mechanism associated with the periphery of said pulley or drum, and means directly operated by the sheet material passing through the machine for releasing said brake mechanism. 115 120

5. In a machine of the class described, the combination of a table provided with a 125 transverse slot at its rear end, a constantly rotating cylindrical drum mounted below the table and having its upper edge or sur-

face lying in a plane parallel to, but slightly above, the plane of the table, a plurality of parallelly arranged pulleys normally in engagement with the surface of the drum and vertically movable with respect thereto, a linkage system connecting said vertically movable pulleys together and terminating in a single vertically movable member whereby, when sheet material is fed through the machine between the pulleys and the drum, the average vertical movement of the pulleys is imparted to the single vertically movable member, a rotatably mounted pulley, a crank pin extending laterally outward therefrom and forming a pivotal connection for the upper end of said vertically movable member, gear teeth formed on a portion of the periphery of said rotatably mounted pulley, a pinion meshing with said gear teeth, an indicating hand attached to said pinion, and a graduated dial cooperating with said indicating hand whereby the average movement imparted to the vertically movable member will be visually indicated on the dial by the indicating hand.

6. In a machine of the class described, the combination of a table provided with a transverse slot at its rear end, a constantly rotating cylindrical drum mounted below the table and having its upper edge or surface lying in a plane parallel to, but slightly above, the plane of the table, a plurality of parallelly arranged pulleys normally in engagement with the surface of the drum and vertically movable with respect thereto, a linkage system connecting said vertically movable pulleys together and terminating in a single vertically movable member whereby, when sheet material is fed through the machine between the pulleys and the drum, the average vertical movement of the pulleys is imparted to the single vertically movable member, a rotatably mounted pulley, a crank pin extending laterally outward therefrom and forming a pivotal connection for the upper end of said vertically movable member, gear teeth formed on a portion of the periphery of said rotatably mounted pulley, a pinion meshing with said gear teeth, an indicating hand attached to said pinion, a graduated dial cooperating with said indicating hand whereby the average movement imparted to the vertically movable member will be visually indicated on the dial by the indicating hand, a brake mechanism associated with said rotatably mounted pulley, and means operable by the sheet material in its passage through the machine for releasing the brake mechanism from the pulley.

7. In a machine of the class described, the combination of a table provided with a transverse slot at its rear end, a constantly rotating cylindrical drum mounted below the table and having its upper edge or surface lying in a plane parallel to, but slightly

above, the plane of the table, a plurality of parallelly arranged pulleys normally in engagement with the surface of the drum and vertically movable with respect thereto, a linkage system connecting said vertically movable pulleys together and terminating in a single vertically movable member whereby, when sheet material is fed through the machine between the pulleys and the drum, the average vertical movement of the pulleys is 70 imparted to the single vertically movable member, a rotatably mounted pulley, a crank pin extending laterally outward therefrom and forming a pivotal connection for the upper end of said vertically movable member, gear teeth formed on a portion of the periphery of said rotatably mounted pulley, a pinion meshing with said gear teeth, an 75 indicating hand attached to said pinion, a graduated dial cooperating with said indicating hand whereby the average movement imparted to the vertically movable member will be visually indicated on the dial by the indicating hand, and a second averaging device associated with the first averaging device for steadyng the movements of the indicating hand.

8. In a machine of the class described, the combination of a table provided with a transverse slot at its rear end, a constantly rotating cylindrical drum mounted below the table and having its upper edge or surface lying in a plane parallel to, but slightly above, the plane of the table, a plurality of parallelly arranged pulleys normally in engagement with the surface of the drum and vertically movable with respect thereto, a linkage system connecting said vertically movable pulleys together and terminating in a single vertically movable member whereby, when sheet material is fed through the machine between the pulleys and the drum, the average vertical movement of the pulleys is 100 imparted to the single vertically movable member, a rotatably mounted pulley, a crank pin extending laterally outward therefrom and forming a pivotal connection for the upper end of said vertically movable member, gear teeth formed on a portion of the periphery of said rotatably mounted pulley, a pinion meshing with said gear teeth, an indicating hand attached to said pinion, a graduated dial cooperating with said indicating hand whereby the average movement 105 imparted to the vertically movable member will be visually indicated on the dial by the indicating hand, a permanent record receiving means movable across the face of the dial, and means carried by the indicating hand for making on said record making 110 means a permanent record of the movements of the indicating hand.

9. In a machine of the class described, the combination of a table provided with a transverse slot at its rear end, a constantly 115

rotating cylindrical drum mounted below the table and having its upper edge or surface lying in a plane parallel to, but slightly above, the plane of the table, a plurality of 5 parallelly arranged pulleys normally in engagement with the surface of the drum and vertically movable with respect thereto, a linkage system connecting said vertically movable pulleys together and terminating in 10 a single vertically movable member whereby, when sheet material is fed through the machine between the pulleys and the drum, the average vertical movement of the pulleys is imparted to the single vertically movable 15 member, a rotatably mounted pulley, a crank pin extending laterally outward therefrom and forming a pivotal connection for the upper end of said vertically movable member, gear teeth formed on a portion of the periphery of said rotatably mounted pulley, a pinion meshing with said gear teeth, an indicating hand attached to said pinion, a graduated dial cooperating with said indicating hand whereby the average movement imparted 20 to the vertically movable member will be 25

visually indicated on the dial by the indicating hand, permanent record material mounted on the dial and movable across the face thereof, means operable during the movement of the sheet material through the machine for moving said record material across the face of the dial and in synchronism with the movement of the sheet material through the machine, and means carried by the indicating hand for making a permanent record 30 on the record material of the movements of the indicating hand. 35

10. In a machine of the class described, the combination of an indicating hand, means for operating said hand controlled by 40 the passage of material through the machine, and brake mechanism for said indicating hand operable by the material in its passage through the machine to release the hand prior to the indicating operation and to lock 45 the hand prior to the complete passage of material through the machine.

In testimony whereof, I have signed my name to this specification.

DANA E. HARDING.
